ATTORNEY.

UNITED STATES PATENT OFFICE.

FRANK LINDSAY, OF DETROIT, MICHIGAN.

RAILROAD GUARD RAIL.

1,414,477.

Specification of Letters Patent. Patented May 2, 1922.

Application filed May 21, 1921. Serial No. 471.

To all whom it may concern:

Be it known that I, FRANK LINDSAY, a citizen of the United States, and residing at Detroit, county of Wayne, and State 5 of Michigan, have invented a new and Improved Railroad Guard Rail, of which the following is a specification.

My invention relates to railroad guard rails and has for its primary object the 10 provision of a guard rail that will support and brace the main rail against both creeping and lateral movement while always maintaining a fixed distance between main and guard rails.

Another object of my invention is to 15 construct the guard rail with integral spacing and supporting members adapted to engage the inner side and bottom respectively of the main rail, and having tie 20 bolts engaging the outer side of the main rail so as to secure the two rails together.

A further object of my invention is to provide a guard rail that can be secured 25 to the main rail after the main rail has been spiked on its inner side as well as its outer, and which can be effectively tied to the main rail so as to prevent separation of the two rails by causing them to travel simultaneously should the main rail chance 30 to move.

A further object is to provide a simple and durable guard rail that can be inexpensively cast with spacers, main rail supports, locking ears and end thrust brackets 35 integral with the guard rail.

Other object and advantages will be apparent from the following description in which reference is made to the accompanying drawing illustrating a preferred embodiment of my invention, and wherein similar reference numerals designate similar parts throughout the several views.

In the drawings:

Fig. 1 is a plan view of a section of 45 railroad track with my guard rails in position adjacent the main rails;

Fig. 2 is a longitudinal section taken substantially on the line 2-2 of Fig. 1 looking in the direction of the arrows, and

Fig. 3 is a detail cross section taken substantially on the line 3-3 of Fig. 1, and

Fig. 4 is an enlarged detail view showing the rail supports.

Referring to the drawings the numeral 55 5 designates the main rails which are se-

cured to ties 6 by spikes 7 adjacent the outer edges of the rails in the usual manner. It is to be noted, however, that with my invention it is possible, and in fact preferred, to have the main rails spiked on their inner edges by spikes 8 so as to further resist lateral or spreading movement. Other railroad guard rails now on the market do not permit of this additional spiking of the rails, in which regard I consider them 60 faulty.

My improved guard rail consists of a short rail 9, curved adjacent its ends, as at 10, in the usual manner of guard rails and integrally cast or otherwise formed 70 with a base plate 11 through which the guard rail may be spiked or bolted to the ties adjacent the inner edges of the main rails. The base plate 11 is provided with main rail supports 12 (see Figs. 3 and 4) 75 adapted to extend under the main rails between the ties to strengthen the main rails and also to provide positioning means for correctly locating the guard rails in position. Preferably the guard rails are 80 secured to the main rails by means of hooked bolts 13 passing through the bifurcations of the main rail supports and depending ears 14 under the guard rail 9, which are apertured to receive the bolts 13 85 substantially as shown in Fig. 3. By turning upon the nuts 15 of these bolts, the hooked end portions are drawn against the outer flanges of the rails and further turning movement brings the guard rails 90 into position adjacent the main rails, which position is determined by spacers or guard cleat 16 (see Fig. 3). The spacers 16 contact the inner flange of the main rail and prevent further movement of the guard 95 rail when the proper position has been reached. These spacers or guard cleats 16 also serve to strengthen the guard rail because of their engaging the lower portion of the web of the guard rail on the 100 side nearest the main rail, and the guard rail is further strengthened by a series of lateral webs 17 formed with the base plate and guard rail and engaging the side of the guard rail away from the main rail 105 in staggered relation to the cleats or spacers 16. By virtue of this construction the guard rail is particularly strong at the points where they are likely to be contacted by the wheels of the rolling stock. 110

To resist creeping movement I preferably form the base plates 11 with end thrust brackets 18 at each extremity of the guard rail and these brackets are apertured to receive spikes or bolts 19 in longitudinal alignment with the main portion of the guard rails. These spikes will firmly secure the guard rails in position after they have been properly spaced beside the main rails by the bolts 13 and spacers 16, resisting especially any tendency toward endwise or creeping movement of the guard rail, and spikes 20 positioned adjacent the webs 17 resist any tendency of the guard rails toward lateral or spreading movement.

While it will be apparent that the illustrated embodiment of my invention herein disclosed is well calculated to adequately fulfill the objects and advantages primarily stated, it is to be understood that the invention is susceptible of variation, modification and change within the spirit and scope of the subjoined claims.

Having described my invention I claim:

1. A railroad guard rail integrally formed with end thrust brackets, spacing cleats, reinforcing webs in staggered relation to the spacing cleats, main rail supports, and locking bolts passing through the guard rail below the spacing cleats.

2. A railroad guard rail integrally formed with end thrust brackets, spacing cleats on the outer side of the rail, and reinforcing webs on the inner side of the rail, and in staggered relation to the spacing cleats, and locking bolts passing through the guard rail in alignment with the spacing cleats.

3. A railroad guard rail having a base plate, spacing cleats integrally formed therewith, main rail supports, depending apertured ears, and locking bolts adapted to pass through the apertured ears and engage the outer flange of the main rail.

4. A railroad guard rail having a base plate, spacing cleats integrally formed therewith, bifurcated main rail supports, depending apertured ears, and hooked locking bolts adapted to pass through the apertured ears and engage the outer flange of the main rail.

FRANK LINDSAY.
